(57) **CLAIM**

The ornamental design for a fastening device pin, as shown and described.

DESCRIPTION

FIG. 1 is a isometric view of a fastening device pin showing the new design;

FIG. 2 is a top view of a fastening device pin showing the new design;

FIG. 3 is a front view of a fastening device pin showing the new design;

FIG. 4 is a side view of a fastening device pin showing the new design;

FIG. 5 is a bottom view of a fastening device pin showing the new design;

FIG. 6 is a other side view of the fastening device pin showing the new design;

FIG. 7 is a another isometric view of a fastening device pin showing the new design; and,

FIG. 8 is a close-up isometric view of FIG. 7 of a fastening device pin showing the new design.

The dash-dash lines depict portions of the fastening device pin that form no part of the claimed design. The dot-dash lines are for the purpose of illustrating the boundary of a corresponding view, and form no part of the claimed design.
